UNITED STATES PATENT OFFICE.

GEORGE KIRCHGRABER, OF ST. LAWRENCE, DAKOTA TERRITORY.

FLOUR-CHEST.

SPECIFICATION forming part of Letters Patent No. 398,736, dated February 26, 1889.

Application filed April 16, 1888. Serial No. 270,769. (No model.)

To all whom it may concern:

Be it known that I, GEORGE KIRCHGRABER, a citizen of the United States, residing at St. Lawrence, in the county of Hand and Territory of Dakota, have invented certain new and useful Improvements in Flour-Chests; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to make the sieve and its supports so that it may be put in and taken out without interfering with the flexible rubber which extends from the hopper-hole nearly or quite to the bottom 20 of the sieve, the raised pocket at one end preventing the sieve from being drawn back and out of the chest.

Figure 1 of the drawings is a vertical section; Fig. 2, a horizontal section on line $x x$, 25 Fig. 1; Fig. 3, a vertical section showing the sieve in a position to be removed; Fig. 4, an end view, partly in section; Fig. 5, a detail perspective view of the sieve.

In the drawings, A represents the chest, 30 and B the hopper, with a hole, b, surrounded by the rubber b', which is flexible, and projects nearly to the bottom of the sieve, so as to guide the flour down to the sieve without spreading it laterally thereon.

35 I is the door through which the sieve is partly drawn back before it is taken out. The sieve is made of a woven-wire fabric, D, on the bottom and sides, said fabric being brought up over the ends of the side pieces, 40 C C, and extended inwardly for some distance to prevent the escape over the ends of the impurities lodging in the pockets c c'. On the bottom of the rabbeted sides C C are made fast the cross-pieces F F, which project 45 beyond them and slide on the cleats G G, made fast to the sides of the chest A, at the same height and directly opposite each other.

Two cleats are on each side with an intermediate open space through which the ends of 50 the cross-pieces F may pass.

E is the rod by which the sieve is moved horizontally back and forth in order to make the flour pass therethrough.

The chest is used as follows: The flour, hav-

ing been emptied from the bag or other receptacle into the chest, finds its way by its own gravity through hopper and rubber spout or guide to the sieve, upon which the lower end of the column rests. When the cook or baker wishes, the sieve is reciprocated 55 until as much as is needed has been deprived of its impurities, which are caught in the pockets. The drawer is then removed to pour the flour into some other receptacle, or the flour is taken out of the drawer without 60 the removal of the latter by a scoop. After the flour has been all used and the chest is empty, the drawer is first removed and then the sieve, so that the impurities may be 65 emptied from the pockets.

70 The sieve cannot be inserted in place or removed therefrom by a horizontal movement on account of the projecting rubber b' and the elevation of the ends c c' above the bottom of sieve; hence the sieve is first drawn 75 to the position shown in Fig. 3 of the drawings, and then carried down to the position shown in dotted lines, when it is drawn out entirely. This operation is reversed in order to put the sieve into place, so that the cross-pieces F shall rest on the cleats G. In both 80 operations the drawer H is first taken out.

I am aware that the chest with top-hinged door and the hopper with projecting rubber about the hole b thereof are old; also, that 85 sieves have been used with pockets; but

What I claim as new, and desire to protect by Letters Patent, is—

1. A flour-chest sieve consisting of the side pieces, C C, covered at the ends by woven 90 wire, and the cross-pieces F F, supporting a bottom of woven wire, pockets c c' being thus formed to extend above and below the sieve-bottom.

2. The combination of a flour-chest having 95 side cleats, G G, and a sieve having cross-pieces F F, extended to rest on them, the cleats and cross-pieces on each side being separated by an intervening space, as shown, whereby the sieve may be put in or taken out, 100 as described.

In testimony whereof I affix my signature in presence of two witnesses.

GEORGE KIRCHGRABER.
